US00D755300S

(12) **United States Design Patent**
Akana et al.

(10) **Patent No.:** US D755,300 S
(45) **Date of Patent:** ** May 3, 2016

(54) **LABEL**

(71) Applicant: **Apple Inc.**, Cupertino, CA (US)

(72) Inventors: **Jody Akana**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Matthew Dean Rohrbach**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **14 Years**

(21) Appl. No.: **29/501,653**

(22) Filed: **Sep. 5, 2014**

(51) LOC (10) Cl. **19-08**

(52) U.S. Cl.

USPC **D20/23; D20/27**

(57) **CLAIM**

The ornamental design for a label, as shown and described.

DESCRIPTION

The FIGURE is a front view of a label showing our new design.

The broken lines in the FIGURE show portions of the label that form no part of the claimed design.

1 Claim, 1 Drawing Sheet

US D755,300 S
